SIEVE LINER

Harry B. Rice, Houston, Tex., assignor to Vacuum
Bolting Cloth Cleaner Corporation, Houston,
Tex., a corporation of Delaware

Application September 19, 1933, Serial No. 690,140

4 Claims. (Cl. 209—382)

My invention relates to liners for sieves or sifting screens and particularly to liners for devices of this character which are commonly used for sifting or screening fine materials such as flour, talcum powder and tooth paste.

Bolting or sifting screens employed for such purposes, and particularly those which operate with a vibratory or gyratory motion, are generally provided with screen cloths of silk or other thin fabric, stretched upon and secured to an open frame or grate. This supporting frame is usually constructed of wooden strips, bars or sections nailed or otherwise secured together, the area within the frame being divided into compartments by cross bars, strips or partitions. Upon the inner surfaces of the frame so formed and partitioned marginal liners are customarily secured by nails or other suitable fastening means. The sieve liners heretofore known and used have been made of fabric strips or of wooden sections. Liners of either of these types, being of a more or less porous nature, absorb a certain amount of moisture and cause particles of the substances being screened to adhere to and remain upon them. Particles of the material being sifted become lodged in the angular corners of the liners upon the frame and in the crevices of the joints between adjacent liner sections. These liners are also objectionable because they wear out rapidly and have to be replaced frequently.

Liners formed of metal strips or plates secured together would be little, if any, more satisfactory than the objectionable wooden or fabric liners. Such metal liners would have the same angular corners and crevices for catching particles of material, as are present in the wooden liners. The increased weight and cost of the metal frames would also be undesirable. Moreover, unless they were formed of some special expensive metal they would be liable to rust and deposit particles of rust or scale in the screened materials.

These objections and defects are especially important and serious in the case of screens or sieves used for screening food materials (for example, flour or salt) or toilet or pharmaceutical powders or preparations (for example, talcum powder, tooth powder, tooth paste and soda). In the screening of materials of this general character it is not only important, but vitally essential, that the cleanliness and purity of the screened material be preserved. Caking of particles of the material upon the frame or liner or in corners or crevices, and/or the introduction of such old and stale caked particles or fragments of dirt, rust or other foreign matter, results in an impure and otherwise unsatisfactory screened product.

The marginal inner liners heretofore provided

are otherwise objectionable. They are usually secured in position upon the screen frame by numerous nails driven through them into the wooden frame. A liner for a single sieve compartment is ordinarily formed of four strips or sections, each held in place by from six to ten nails. In the operation of the screens it is necessary from time to time to remove the liners for cleaning purposes or to replace worn liners. Each time this is done from twenty-four to forty nails must be withdrawn from and reinserted into the wooden frame. This results in great damage to the frame, rendering it incapable of having liners attached to it and compelling it to be discarded and replaced while it is otherwise in satisfactory operative condition.

One of the principal objects of my present invention is the provision of a sieve or screen liner which will present a smooth unbroken surface to the material on the screen, and which will be free of joints, crevices or recesses in which the material might lodge and be retained.

Another object is the provision of a unitary sieve liner of convenient and efficient form which may readily be applied to and removed from a screen, with comparatively little, if any, damage to the screen frame.

A further object is the provision of a sieve liner of resilient, flexible and elastic material or composition which is readily adjustable to sieves of different sizes, shapes or dimensions, and which will, by reason of its resiliency, increase the activity and promote the effective functioning of sieve cloth cleaners operatively positioned relative to the sieve.

A still further object is the provision of an integral sieve liner, which may be readily and economically produced of rubber, rubber composition or other suitable preferably resilient moldable material.

The invention by which these objects are realized comprises a liner shaped, formed and constructed in the manner illustrated in the accompanying drawing and more fully explained and defined in the following description and claims:

In the drawing:

Figure 1 is a perspective view of the preferred form of the liner which constitutes my invention.

Figure 2 is a top plan view of a sifting screen or sieve comprising a marginal frame and partitions with sieve cloth and cleaner support secured thereto and showing my sieve liner in position in one of the compartments, the frame and sieve cloth being partly broken away.

Figure 3 is a vertical sectional view of the screen or sieve on line 3—3 in Figure 2, with my liner in position and a cloth cleaner device operatively associated therewith, and

Figure 4 is a central sectional view of my cloth cleaner shown in Figure 3.

My liner is designed to be applied to a frame B, preferably composed of side pieces or strips 6 11 and end pieces 12, and supporting a sieve cloth 13 of silk or other suitable fabric and a sieve cleaner support 14 preferably of reticulated metal. The frame is preferably divided into sections or compartments by partitions 15 and 10 16 in the usual manner.

The improved sieve liner which constitutes 15 my present invention is a unitary integral endless strip or open frame A preferably of rectangular or generally rectangular shape. In its 20 preferred form the outer sides which fit against the inner surfaces of the sieve frame B are flat, as are also the top 1 and bottom 2 of the liner. The inner sides 3 of the liner may be beveled, curved or rounded, but are preferably 25 flat plane surfaces with the corners 4 rounded.

While my liner is preferably of rectangular 30 form or shape, and is so illustrated, it may be of circular or annular form or of any shape and/or dimensions necessary to adapt it to 35 screen frames of other shapes and dimensions. The necessity of producing liners of different dimensions is largely eliminated, however, by the flexibility and elasticity of my liner, any individual liner being capable of considerable 40 stretching to fit frames of different shapes and sizes.

The adaptability and adjustability of my liner 45 are of particular importance and usefulness. The liner is made in one piece, preferably in a 35 mold of suitable construction. It combines the desirable attributes of firmness, resiliency, flexible adjustability and long life. These characteristics are inherent in the liner by reason of the material of which it is formed. The material 50 best suited for this purpose is soft smooth rubber of non-blooming stock, cured without sulphur, or closely similar rubber composition. Such materials are well known, being commonly employed in the various arts for cushioning and shock absorbing purposes.

My invention is not limited to the use of any 55 specific rubber or rubber composition, as any kind of rubber, rubber composition or other suitable plastic composition may be employed which 60 is adapted to form a tough wear-resisting and semi-rigid but flexible and resilient rubber-like strip or frame of smooth texture.

My liner is readily secured in position and, 65 because of its resiliency, clings or adheres closely to the frame. It may be nailed or otherwise secured to the frame. If nails are used one or two small nails in each of the rounded and 70 preferably thickened corners will be sufficient. By virtue of its flexibility a liner embodying my invention is not restricted in its use to any one frame of certain shape or dimensions. The liner may be, and preferably is, made sufficiently thin to have considerable flexibility and elasticity and any one or more of its sides may 75 consequently be stretched lengthwise in the same manner as an ordinary heavy rubber band. In this way my liner may be stretched to fit sieve frames of various sizes and shapes. It may be used either above or below the screen cloth, or in both locations, where the particular frame construction permits or renders such use of the liner possible and desirable or useful.

The liner is easily and quickly applied and 80 firmly held in place. It is usually applied and secured to the frame in stretched condition.

Under certain conditions the natural resiliency of the liner exerts sufficient gripping action to hold it in position when it is compressed and sprung into the frame. Various other modes of securing the liner in position may be used. If nails are employed, only a few small nails in the corners will be needed, no nails or other fastening means between the corners being required. In this respect my liner is a considerable improvement over the fabric and sectional 10 wooden liners heretofore known and now in use, which require nails entirely around all sides, the total number necessary being several times the number required for my liner. The damage to the wooden sieve frames which results from the 15 repeated driving and withdrawal of so large a number of nails is obviated or greatly lessened by the use of my one piece resilient liner. The application of my liner to a screen frame is much more simple than the matter of securing fabric or sectional wooden liners in place. There is a considerable saving of time and trouble.

My liner also possesses the advantage of completely filling up the corners of the frame, which the fabric liners now in use cannot accomplish, and of eliminating altogether the existence of the angular corners, joints and crevices always present in the wooden liners now in use, which are formed of four sections. One of the points 30 of superiority of my liner, therefore, is that it is clean and sanitary, particularly because it is not porous, permits no particles of material to cling to it, and affords no recesses for the collection of particles of dirt or for the hibernation of weevils.

An additional feature of advantage of my liner, as compared with the known fabric and wooden liners, is its usefulness in association 40 with sieve cloth cleaners.

In order to obtain a satisfactory sifting operation, it is essential that the meshes of the screen cloth be maintained in free and open condition. To this end cleaners of various kinds have been designed to knock or jar the fine 45 screen cloth of vibrating screens so as to loosen the material from the meshes of the screen and throw it upwardly. The result sought by all such devices is to maintain the mass of material in a constant dancing motion. The efficiency 50 of such devices depends in large measure upon their activity, i. e., upon the rapidity and extent of their movement. Among the schemes proposed for accomplishing the desired result, balls or other loose pieces of metal have been 55 arranged upon a reticulated or screen-like support (similar to the cleaner support 14 shown herein), the support being disposed below the screen cloth 13 to be cleaned and so spaced from it that the loose pieces would at frequent 60 intervals strike the screen cloth when the cloth and the lower support were vibrated together.

A form of screen cloth cleaner device which I have invented and found to be more efficient and generally more satisfactory than prior devices comprises a soft body of rubber or rubber composition in the form of a substantially flat upper surface and having upon its lower surface an integrally formed rounded knob. This device is described and claimed in a copending application, Serial No. 652,215, filed January 17, 1933.

In use, one or more of my cleaner devices are placed upon a support 14 of wire, fabric or any other suitable material immediately beneath the screen cloth 13 to be cleaned. The screen 75

cloth 13 and support 14 may be secured in fixed relationship in the frame A, which may be vibrated, oscillated, gyrated or otherwise agitated by any suitable mechanism (not shown) in the 5 performance of sifting or screening operations. Both the cleaner device and sieve liner, however, are adapted to be used upon sieves or screens of this general character whether the support 14 is fixed to vibrate with the screen cloth 13 or 10 is separate therefrom and itself either movable or stationary. The screen cloth may be of any suitable character and mesh. The support 14 is preferably reticulated and of relatively coarse mesh, but may be imperforate where the machine in which it is used is of such design as to permit.

In the operation of the sieve or screen illustrated herein, the screen cloth 13 and support 14 are vibrated or otherwise agitated as a unit. 20 The cloth cleaner devices C rest upon their rounded knobs 22 upon the support 14, their upper surfaces being either in contact with the screen cloth or sufficiently close thereto to contact therewith during the operation of the screen. Agitation of the frame carrying support 14 and screen cloth 13 gives the cleaner devices a slight but efficient bounding or bouncing movement accompanied by constantly varying tilting movements occasioned by the unbalanced condition of the devices upon their rounded knobs 22. The cleaner devices consequently strike the screen cloth 13 at frequent intervals but at different points and varying angles. Sometimes the entire top face of the device 25 strikes flatly against the under side of the screen cloth, on which occasions the recess 24 exerts an action similar to that of a vacuum cup; the device attaches itself momentarily to the cloth and is released by the continued vibration 30 of the screen cloth 13 and support 14. At other times first one edge of the cleaner and then another is tilted against the screen cloth. This tilting, bounding and cupping action is continuous.

45 The cleaner is ordinarily sufficiently active and its contacts with the screen cloth sufficiently violent to afford ample and satisfactory cloth cleaning action. Its efficiency is increased, however, when a screen cloth cleaner C of this 50 character is used in a screen fitted with the resilient liner A disclosed in my present application. When so used, the cleaner device of resilient material, in the course of its movement upon the vibrating support 14, comes frequently 55 into contact with the liner A, and rebounds therefrom, the rebounding action being amplified by the resiliency of the liner.

These contacts occur at points on the liner between the corners, the cleaner practically 60 never striking the liner at the corners where the nails may be located.

Hence, no matter how badly worn my liner may become, the cleaner device used with it cannot be injured by contact with exposed nail 65 heads. In this respect my resilient liner is superior to the old fabric and wooden liners which are secured by nails throughout their extent. When these old liners begin to wear away through continued use, the nail heads are left 70 exposed along the sides of the frame, between corners where the cleaner repeatedly strikes. The result, of course, is excessive wear of and

damage to the cleaner device. The avoidance of this damage by the use of my liner is a distinct benefit, regardless of the type or form of cleaner device which may be associated with it.

As previously indicated, the cleaner device C, which is most advantageous in connection with my liner A, comprises a body 21 preferably in the form of a generally flat rectangular shape, provided on its under side with a rounded supporting knob or button 22 preferably integral with the body 21. The knob or button may be made entirely of the same rubber, rubber composition or other resilient plastic material of which the body 21 is composed, the whole being formed integrally preferably by moulding. Or the knob may be composed wholly or partially of a rounded metal head, cap or insert 23 seated upon or embedded in the knob 22, in order to provide a relatively hard wear-resisting surface at the point of most frequent contact with the metal of the support 14. The preferred manner of producing the device is to mold the entire device in one piece with the metal insert 23 incorporated as a part of the integrally formed rounded knob 22.

The body 21 of the cleaner is preferably formed with a recess 24 on its upper side. This recess may vary in size and shape, but for best results should be circular, or substantially circular, and of a diameter and depth sufficient to effect a cupping or vacuum action upon the screen cloth 13 when the upper surface of the body 21 comes into contact with the cloth.

My cleaner device may be made of different 35 shapes and proportions. Both the cleaner and the liner described herein may be used with sifting or shaking screens of different kinds for various materials as well as flour and the other substances specifically mentioned. My invention is not limited to the dimensions of the liner or of the cleaner, as illustrated, the drawing merely showing the preferred form of embodiment of each.

I claim:

1. A liner for sieves comprising an integral frame-like body of rubber composition adapted to be secured to the inner surface of a sieve frame, and having relatively thin flexible side and end walls and relatively thick corners 50 rounded on their inner surfaces.

2. A sifting apparatus comprising a frame, a screen cloth secured upon said frame and an integral endless elastic rubber liner secured to the inner surface of said frame adjacent said screen cloth and extending entirely around the margin thereof.

3. A liner for sieves comprising an integral endless body adapted to be secured to the inner surface of a sieve frame, said body having relatively thin elastic portions adapted to be positioned against the walls of said frame and spaced relatively thick portions on said body to fit the corners of said frame.

4. A sifting apparatus comprising a frame, a screen cloth secured upon said frame, and an endless elastic liner extending entirely around the inner surface of said frame adjacent said screen cloth and secured thereto in stretched condition.

HARRY B. RICE.
